NO. 36,387.

Patented June 30, 1903.

UNITED STATES PATENT OFFICE.

EUSTACE CREEES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS OR SIMILAR ARTICLES.

SPECIFICATION forming part of Design No. 36,387, dated June 30, 1903.

Application filed May 8, 1903. Serial No. 156,322. Term of patent 7 years.

To all whom it may concern:

Be it known that we, EUSTACE CREEES and CHARLES S. COURT, both citizens of the United States, residing in the city of Providence, in the county of Providence and State of Rhode Island, have invented a new, original, and ornamental Design for the Handle of a Spoon or Similar Article, of which the following is a specification, reference being had to the accompanying drawings, forming part thereof.

Figure 1 is a view of the obverse side of a spoon-handle embodying our new design, and Fig. 2 the reverse side of the same, both sides of the design being in relief.

Having described our invention, what we claim is—

The ornamental design for the handle of a spoon or similar article, substantially as shown.

In testimony whereof we have affixed our signatures in presence of two witnesses.

EUSTACE CREEES.
CHARLES S. COURT.
